N. BINGHAM.
DETACHABLE SURFACE PACKER.
APPLICATION FILED JUNE 29, 1912.

1,054,899.

Patented Mar. 4, 1913.

UNITED STATES PATENT OFFICE.

NELSON BINGHAM, OF ERIE, NORTH DAKOTA.

DETACHABLE SURFACE-PACKER.

1,054,899.

Specification of Letters Patent. Patented Mar. 4, 1913.

Application filed June 29, 1912. Serial No. 706,752.

To all whom it may concern:

Be it known that I, NELSON BINGHAM, citizen of the United States, residing at Erie, in the county of Cass and State of North Dakota, have invented certain new and useful Improvements in Detachable Surface-Packers, of which the following is a specification, reference being had therein to the accompanying drawing.

10 This invention relates to surface packers, and has for its object the production of a simple and efficient surface packer, and a detachable shield therefor, whereby the shield may be attached in such a manner as to 15 allow the packer to effectively operate to constitute a surface, and sub-surface packer.

Another object of this invention is the production of a simple and efficient packer casing or shield which may be quickly and 20 efficiently secured to the packer.

With these and other objects in view, this invention consists of certain novel constructions, combinations, and arrangements of parts, as will be hereinafter fully described 25 and claimed.

In the drawing:—Figure 1 is a side elevation of one section of the packer. Fig. 2 is a top plan view thereof, showing the same partly in section. Fig. 3 is a central transverse section through a series of packer disks. Fig. 4 is a detail perspective of a portion of the packer shield or casing.

By referring to the drawings it will be seen that the ordinary disks 1 may be employed, which have beveled outer faces, as indicated in Figs. 2 and 3, and between these disks 1 are positioned sub-surface disks 2. The disks 1 are supported upon a supporting shaft 3, and the sub-surface packing 40 disks 2 are provided with sockets 4, within which sockets are placed filling collars 5. The casing or protector 6 is placed upon the surface and sub-surface packers 1 and 2, as indicated in Fig. 2, and this protector 6 comprises a primary and auxiliary section, as indicated in Fig. 1. Each of the sections is provided with a substantially V-shaped portion 7, which fits over the sub-surface packing disk 1, and a plurality of laterally 45 extending spaced packing members 8 direct from the substantially V-shaped portion 7, as indicated in Fig. 2. The end packing member 9 of each section is formed L-shaped in cross section and the abutting faces of these members 9 are held together by means 50 of a bolt 10. In this manner, it will be seen

that the primary and auxiliary sections of the protector will be firmly held upon the disks.

From the foregoing description, it will be 60 readily seen that a very simple and efficient device has been produced which may be readily attached to the surface and sub-surface packer in such a manner as to allow both the surface and sub-surface of the soil 65 to be efficiently packed. It will be further seen that a simple protecting casing has been produced which may be readily detached from the packer disks.

The outer edges of disks 2 are smooth and 70 it will, therefore, be seen that the spaced packing members 8 will constitute an efficient packing means for the soil especially where the packer is used in soft, sandy soil. By having these spaced packing members 75 so carried upon the smooth outer faces of the disks 2, it will be seen that the packer will very efficiently operate upon soft soil and will not merely form a hard crust upon the surface of the soil as would be the case 80 if the entire surface of the packer were smooth.

Of course it should be understood that the present device may be used with or without the casing or protector 6, thereby 85 allowing the disks 2 to be used as a surface packer and the disk 1 to be used as a sub-surface packer. These disks may be employed in this manner without the casing or protector 6 when using the packer upon 90 hard soil, but where the device is to be used upon soft or sandy soil the casing or protector 6 is placed upon the disks 1 and 2. It should be understood, as illustrated clearly in Fig. 3, that when the casing or 95 protector 6 is placed upon the disk 1, the disk 1 will be entirely or completely covered, the lugs 8 extending upon either side thereof and overhanging the upper edges of the disks 2.

100 What is claimed is:—

1. A device of the class described comprising a sub-surface packing disk, a surface packing disk placed upon each side of said sub-surface packing disk, said surface 105 packing disks provided with sockets upon their outer faces, filling collars positioned within said sockets, casings positioned over said sub-surface packing disks and provided with spaced packing members overhanging 110 the edges of said surface packing disk.

2. A device of the class described com-

prising a sub-surface packing disk, a pair of surface packing disks, a sectional casing positioned upon said packing disks, each section fitting over said sub-surface packing disk and terminating in laterally extending spaced packing members, each section of said casing provided with a packing member at each end L-shaped in cross sec-

tion, and means passing therethrough for securing said sections together.

In testimony whereof I hereunto affix my signature in presence of two witnesses.

NELSON BINGHAM.
